UNITED STATES PATENT OFFICE

170,597

WHEEL COVER MEMBER OR SIMILAR
ARTICLE

George Albert Lyon, Detroit, Mich.

Application December 1, 1952, Serial No. 22,505

Term of patent 14 years

(Cl. D14—30)

To all whom it may concern:

Be it known that I, George Albert Lyon, a citizen of the United States and a resident of the city of Detroit, in the county of Wayne and State of Michigan, have invented a new, original, and ornamental Design for a Wheel Cover Member or Similar Article, of which the following is a specification, reference being had to the accompanying drawing, forming a part thereof.

On the drawing:

Figure 1 is a side elevational view of my novel design for a wheel cover member or similar article;

Figure 2 is a profile view showing the cross sectional contour of the cover member of Figure 1; and

Figure 3 is a fragmentary side perspective view of the cover member.

The dominant features of my design reside in the portions shown in full lines.

I claim:

The ornamental design for a wheel cover member or similar article, substantially as shown and described.

GEORGE ALBERT LYON.
